TRAFFIC CONTROL APPARATUS

John L. Barker, Norwalk, Conn., assignor to Automatic Signal Corporation, East Norwalk, Conn., a corporation of Delaware

Application May 31, 1939, Serial No. 276,499

19 Claims. (Cl. 177—337)

This invention relates generally to road traffic control apparatus for the control of right of way traffic signals at intersections of traffic lanes, streets and highways. There are two general types of such control, one commonly classified as fixed time control and the other as traffic actuated control. In the case of the fixed time control the usual traffic signals such as green, amber and red lights ordinarily provided for each street are operated by a timing mechanism through a predetermined cycle which is continuously repeated whether there is traffic present or not, the cycle including alternate green signal periods for the intersecting streets for example, with a red signal displayed to one street during the green signal period of the other street, and with one or both amber signals displayed at each change from green to red.

In the traffic actuated type of control, instead of continuously repeating the display of the green, amber and red signals, the control mechanism or controller normally rests with the go signal displayed to one street and the stop signal displayed in the other. One or more traffic detectors in the form of vehicle actuated devices or pedestrian actuated pushbuttons are located in the street to which the stop signal is displayed when the controller mechanism is at rest. An actuation of one of these detectors will cause the controller to start up and go through a cycle of operations during which the go signal is displayed alternately to the two streets and after which the controller will again come to rest with the stop signal displayed in the street wherein the detectors are located and with the go signal displayed in the other street.

Both of these types of traffic control are well known in the art. The purpose of this invention is to provide an apparatus by which a traffic controller of the first type which normally operates continuously can readily be converted into one of the second or traffic actuated type. It is arranged to do this with a minimum of change in the fixed time timer which is to be so converted.

A fixed time traffic controller usually consists essentially of a camshaft bearing cams which make and break electrical circuits controlling red, green and amber signals on the two streets. This camshaft is driven by a motor. By the use of the adaptor apparatus disclosed herein such a fixed time controller can be converted into a traffic actuated controller without changing any of the internal circuits of the fixed time controller except the motor circuit which is ordi-

narily easily segregated from the signal circuits for external control connection.

In converting a fixed time control system to a traffic actuated control system some traffic detector means must first be provided to determine the presence of traffic on one of the intersecting streets, usually the side street at an intersection with a main highway. Such a detector may be a pushbutton, which may be operated by pedestrians, or may be an electrical contact device set into the roadway to be operated by vehicle wheels, or may be a magnetic or sound actuated or energy beam actuated device which operates an electrical contact from the magnetic influence or sound of passing vehicles or from the interruption of an energy beam by passing vehicles, for example. Various forms of these devices are already well known in the art.

Having provided some traffic detector means, the principal differences between a fixed time controller as discussed above and a simple form of traffic actuated controller are essentially two. First, the timing motor of the controller must be interrupted, preferably at the end of the highway green period, in the absence of cross street traffic detector actuation, and must be energized again upon cross street detector actuation; and second, any detector actuation occurring in the cross street amber or highway green periods must be stored until after the end of the highway green period so that such actuation will thereby maintain the motor energized at the end of the highway green period and cause another signal cycle to provide a cross street green signal period for itself. Thus for this second difference some latching device such as a "lock-in" relay for example must be provided, and such relay when once energized by a momentary traffic detector actuation at any time except in the cross street green period must be "locked-in" or maintained energized until the next cross street green period. In accordance with the present invention an adaptor apparatus is provided to add the features required to overcome these differences discussed above and thereby adapt or convert a fixed time signal controller to a traffic actuated type.

In the arrangement disclosed herein the adaptor apparatus is interposed between the signals and fixed time controller cam contacts normally controlling the signals. The adaptor apparatus comprises essentially a set of relays operated by the normal signal output current of the fixed time controller, the relays in turn operating the signals. The adaptor is arranged so that its output signal cycle can be varied from the

cycle received from the fixed time controller. The adaptor can receive any of the standard signal cycles from the fixed time control and in turn give out either that cycle or any other of the standard signal cycles commonly in use, as is hereinafter more fully explained.

It is an object of this invention to provide an apparatus for converting a fixed time traffic signal controller into a vehicle actuated traffic signal controller.

It is another object of the invention to provide an apparatus of this type which is capable of causing the traffic signals to operate on any one of several cycles without the necessity for changing the output cycle of the fixed time controller which operates the adaptor.

It is a further object of this invention to provide an apparatus of the type described which is capable of receiving any one of several signal cycles from a fixed time controller and of causing the signals to operate either on the cycle received from the fixed time timer or upon some other cycle.

It is a further object of this invention to provide an adaptor of the type described in which momentary interruptions of the output current of the fixed time controller due to such causes as faulty contacts or irregular cam surfaces will not interrupt the signal normally accorded to traffic by the adaptor.

It is also an object of this invention to provide an adaptor of the type described which can be operated by the signal currents of a fixed time controller without the necessity for rearranging any of the circuits within the fixed time controller other than the motor circuit which can be easily segregated.

A better understanding of this invention can be had by referring to the drawing. At either side of the drawing will be seen the power supply wires, which ordinarily supply alternating current but which are identified as positive and negative for convenience of reference. In the upper left corner is shown a fixed time cycle controller consisting of a camshaft S with cams C1 to C7 inclusive operated by the motor M. This camshaft is shown diagonally with respect to the corners of the drawing. Directly below the camshaft are two relays numbered respectively 6 and 7 which constitute part of the adaptor. These relays are operated by the opening and closing of cam contacts pairs 9, 10, 11, 12, 13, 14 and 15, one contact of each pair being connected directly to the positive power wire.

In the lower center of the drawing is a relay numbered 8 which is also part of the adaptor. This relay is controlled cooperatively by the traffic detectors 23 shown in B street at the street intersection in the lower right part of the drawing and by relays 6 and 7. The three relays 6, 7 and 8 cooperate to control the traffic signals shown in the lower right part of the drawing as disposed along two intersecting streets A and B.

The traffic detectors 23 can be set in the roadway as shown or they could be of the push-button type and be mounted adjacent to the roadway for the use of pedestrians. Detectors of both types are often used so that vehicular traffic and pedestrians can operate the signals. In the lower left corner of the drawing is a transformer T which is preferably used to provide a source of low voltage for traffic detectors and to provide proper voltage for operating

relays 6 and 7 in series with the condensers 33 and 22.

The adaptor comprises relays 6, 7 and 8 with their several armatures and contacts, transformer T and condensers 22 and 33 as well as the associated circuits connecting these parts to each other and to the signals and to the fixed time controller.

The arrangement of cams shown on shaft S 10 of the fixed time controller could be used to give various signal sequences were the signals to be connected directly thereto. Cam C1 could be used to provide two amber periods per cycle common to both streets. Cams C2 and C3 would 15 provide alternate red and green signal indications lasting one half of a cycle each. Cams C4 and C5 would give slightly shorter alternate red and green signal indications not overlapping the amber periods. Cams C6 and C7 would give 20 one independent amber period per cycle for each street.

Switches 19 and 32 permit connecting the coil of relay 6 to the half cycle cam contacts 10 and 11 or the shorter period cam contacts 25 12 and 13. Switches 16, 69 and 73 permit connecting the coil of relay 7 directly to amber cam contacts 14 and 15 or to the common amber cam contact 9 through armature 63 of relay 6. Switches 17 and 18 permit connecting the coil of 30 relay 7 to the short period cam contacts 12 and 13. By properly setting these various switches any of several standard output cycles of a fixed time controller can be selected as the input cycle of the adaptor. The adaptor will 35 operate similarly on any of these cycles as will be further described below.

The chart in the upper right corner indicates the periods during which the several cam contacts are closed. The heavy line on the same 40 level with each cam indicates that portion of the cycle during which the contact is closed and the light line on the same level indicates the position of the cycle during which the contact is open. Thus in the top line the closure of contact 9 during both of the change periods is indicated by the heavy lines in periods 2 and 4 45 of the chart. Similarly the second level of the chart indicates that contact 10, associated with cam C2, is closed during the time indicated by periods 1 and 2, i. e., during one of the green 50 periods and the subsequent change period of the fixed time controller. Contact 10 is open during the time indicated by periods 3 and 4. The next succeeding five lines below indicate the portion 55 of the cycle of the fixed time controller during which contacts 11, 12, 13, 14 and 15 are closed. The line in the chart numbered 60 indicates when relay 6 is energized, the energized period being indicated by the dark line. Similarly line 60 70, the bottom line on the chart, indicates when relay 7 is energized. Relays 6 and 7 will operate as indicated in lines 60 and 70 respectively of the chart provided the fixed time controller puts out any one of the commonly used traffic signal 65 sequences as explained before.

The designations "A green," "A amber," "B green," and "B amber" at the bottom of the chart indicate the parts of the cycle during which the named signal would be energized. Switches 48, 70 52, 56, 61 and 65 are used to control the output signal sequence of the adaptor.

By setting these switches the A green signal can be caused to remain energized during the A amber period or the B green signal can be caused to remain energized during the B amber

period. Similarly the amber signal in either street can be made to follow the green period only or to follow both the green period and the red period. The red period can be caused to coincide with the green period in the opposing street or it can be extended into the amber period thereof. Thus any of the standard traffic signal cycles can be obtained by the proper setting of these switches. Their use for this purpose will be explained in detail below.

As shown in the drawing the apparatus is at rest with the timer motor M deenergized and the camshaft S consequently not revolving. Relay 6 is deenergized. Relay 7 is energized having been operated through the circuit starting at positive power thence through cam contact 15 and switch 73 to the coil of relay 7, thence through condenser 22 to negative power at 67. A parallel circuit is also established feeding power to the right side of the coil of relay 7 through armature 21 of relay 7 and wire 20.

The green signal on A street designated as AG is energized through the circuit starting at positive power thence through switch 78, armature 40 of relay 6, wire 41, armature 42 of relay 8, through its upper contact into wire 43 and switch 65 to the signal AC thence through wire 59 to negative power. The B street red signal, designated BR, is energized through the circuit starting at positive power, switch 78, armature 40 of relay 6, wire 64 thence upward into switch 48 and through wire 49 into the signal BR thence through wire 58 to negative power. No other signals are energized.

A vehicle operating either detector 23 on B street will feed negative power into the coil of relay 8 through wire 24. From the other terminal of relay 8, the circuit goes through armature 25 to coil 26 of transformer T thence to ground. Coil 26 provides a low voltage suitable for operating relay 8 through the detector 23. Relay 8 will thereupon operate and hold itself in the operated position through its armature 28 which bypasses the detectors and supplies negative power to the right side of its coil. Relay 8 will then remain operated until both armatures 25 and 62 are simultaneously open which condition will occur later when the green signal is given to B street.

The energization of relay 8 does three things.

(1) It starts the motor M through armature 30 which completes a circuit directly from positive power via wire 75 through the coil 29 of motor M to negative power.

(2) It deenergizes the A street green signal AG through opening the circuit previously traced to this signal at armature 42 of relay 8.

(3) It energizes the A street amber signal AY through the circuit starting at plus power, switch 78, armature 40 thence via wire 64 to armature 45, then through the upper contact thereof to armature 44 which feeds into wire 47 connected to the A street amber signal AY then through wire 58 to negative power.

Camshaft S of the fixed time control is now revolving in the direction indicated by the arrow above its driving disc. In the connection shown in the drawing cam contact 9 associated with cam C1 can be neglected inasmuch as switch 16 is open. At the end of the A street amber period several changes will take place in the circuits associated with the cams substantially simultaneously.

Cam C7 will open contact 15 and cam C5 will close contact 13. This will have no immediate

effect on the apparatus inasmuch as relay 7 is already energized through the bypass circuit including its own armature 21 as previously mentioned.

5 Also at this time cam C2 will open contact 10 and cam C3 will close contact 11. The effect of this is to remove positive power from the left side of the coil of relay 6 and to connect positive power to the right side of the coil of relay 6 through switch 32. Relay 6 will thereby be energized through the circuit from positive power to cam contact 11, switch 32, the coil of relay 6 thence through condenser 33 to the negative power transformer tap 67. A bypass circuit supplying positive power to the right side of the coil of relay 6 is thereupon established through the closure of armature 34 against its contact. Relay 6 will now definitely remain energized until cam C2 closes contact 10. The operation of relay 6 terminates the A street amber period and inaugurates the B street green signal period.

Upon the operation of relay 6 armature 36 thereof engages its contact and supplies positive power through wire 37 to the coil 29 of motor M thereby assuring that motor M will continue to be energized independently of the circuit through armature 30 previously described. Relay 8 will now be deenergized by the separation of armature 25 from its contact thereby opening the power supply to the left side of the coil of relay 8. Actuation of the detectors 23 are of no effect during the "B" street green signal period because armature 25 and armature 62 are both disengaged from their contacts thus opening the circuit to the left coil terminal of relay 8. During all other parts of the signal cycle either one or both of these armatures will be engaging its contact thus making relay 8 responsive to actuations of detector 23.

35 40 Armature 40 of relay 6 disengages from its lower contact thereby opening the previously described circuit feeding the A street amber signal AY. This last circuit is also opened at armature 44 of relay 8 shortly thereafter. As armature 40 engages its upper contact it supplies positive power through wires 50 and 51, switch 52 to the A street red signal AR thence to wire 59 to negative power. Also armature 40 establishes through its upper contact a circuit from positive power through wire 50, armature 54, wire 55 and switch 56 to the B street green signal BG thence through wire 58 to negative power. The signal indications have now changed to accord the right of way to B street.

55 59 The camshaft S continues to revolve, timing the B street green signal period. At the end of the B street green period cam C6 will close contact 14 and feed positive power through switch 69 and resistor 39 into the left side of the coil of relay 7. This will cause relay 7 to become deenergized since the right side of the coil is also connected to positive power and resistor 39 has a relatively low resistance.

65 70 Armature 21 of relay 7 will thereupon drop into its lower position opening the positive power bypass circuit previously traced to the right side of the relay 7 coil. As armature 21 engages its lower contact it provides an additional source of positive power to coil 29 of motor M so that this motor shall remain running throughout the cycle despite changes which may occur in its other feed circuits. Armature 54 of relay 7 also disengages from its upper contact thereby extinguishing the B street green signal, the circuit for which was previously traced over wire 55. As

this armature engages its lower contact it energizes the B street amber signal BY through wire 57. Armature 62 of relay 7 engages its contact thus providing a circuit to the left coil terminal of relay 8. Relay 8 will now be energized by the next actuation of either detector 23 if any.

The camshaft of the fixed time control continues to revolve, timing the B street amber period which ends when cam C3 opens contact 11 and cam C2 simultaneously closes contact 10. When this occurs positive power is fed to the left side of the coil of relay 6, via switch 19 and low resistance 31 which causes this relay to be deenergized since the right side of relay 6 already has positive power connected via armature 34. Armature 34 thereupon separates from its contact removing the bypass positive power feed circuit to the right side of relay 6.

Armature 36 also now disengages from its contact but this is of no immediate effect since positive power is fed to the coil 29 of motor M through the bottom contact of armature 21. Armature 40 disengages from its upper contact thereby extinguishing the B street amber signal the circuit for which was previously traced. As armature 40 engages its lower contact it energizes the B street red signal through wire 64, switch 48, wire 49, signal BR and wire 53 to negative power. Simultaneously armature 40 energizes the A street green signal AG through wire 64, armature 45 and wire 43 and switch 65 thence through signal AG and wire 59 to negative power. Armature 25 engages its contact thereby providing an additional auxiliary circuit to the left coil terminal of relay 8.

The camshaft S of the controller continues to revolve, timing the normal A street green signal period, energy to motor coil 29 being fed through armature 21 of relay 7 and its lower contact. When the normal A street green period has expired cam C7 closes contact 15 thereby supplying positive power to the right side of the coil of relay 7 through switch 73. Inasmuch as both cams C4 and C6 are disengaged from their respective contacts 12 and 14 no positive power is fed to the left side of the coil of relay 7. Therefore relay 7 will be energized through its circuit previously described and will operate to raise its several armatures. Armature 21 will thereupon engage its upper contact and supply a bypass path for positive power to the right side of the coil of relay 7. As armature 21 disengages from its lower contact the motor coil 29 becomes deenergized since armatures 30 and 36 are also disengaged from their contacts, assuming that no further detector actuation has occurred to energize relay 8. Armature 54 disengages from its lower contact and engages its upper contact but this has no immediate effect on the system inasmuch as no positive power is being fed to armature 54 at this time due to the fact that armature 40 is not engaged with its upper contact. Armature 45 disengages from its lower contact thus interrupting one circuit which feeds the A street green signal over wire 43. However, the A street green signal does not go out at this time since it is fed through a bypass circuit including armature 40, wire 41 and armature 42 of relay 8 over wire 43. The fact that armature 45 engages its upper contact is of no effect because armature 44 of relay 8 is not engaged with its contact. The apparatus, having timed the normal A street green signal period, has now returned to its rest position with the A street green and the B street red signals remaining energized.

Had there been an actuation of either detector 23 during the B street amber period or the normal A street green period relay 8 would have been energized and locked in the energized position through its own armature 28. Had this been the case coil 29 of motor M would not have been deenergized by the breaking of armature 21 from its lower contact since armature 30 of relay 8 would have been in engagement with its contact thereby feeding positive power to the coil 29. Also with relay 8 energized as described the operation of relay 7 would have extinguished the A street green signal AG through the separation of armature 45 from its lower contact because the bypass circuit previously described through wire 41 and armature 42 of relay 8 would have also been open. Furthermore with relay 8 operated the contact of armature 45 with its upper contact would have energized the A street amber signal AY through its usual circuit inasmuch as armature 44 of relay 8 would be engaged with its contact. Hence we see that if there had been an actuation during the preceding B street amber period or the normal A street green period the apparatus, instead of coming to rest at the end of the normal A street green period with the A street green signal and the B street red signal energized, would have continued and started a new cycle which would be the same as that previously described.

Cam C5 may affect the operation of relay 7 during the first cycle after the signals are turned on. Its contact 13 is connected through switch 18 into the supply circuit for the coil of relay 7 in parallel with cam contact 15. It operates as follows. Assume that when the controller was last turned off relay 7 was energized but cam C7 had opened contact 15. When the control is turned on again contact 15 being open and the circuit through armature 21 having been opened when the control was turned off, relay 7 will depend for its immediate energization on the closure of contact 13. The fact that cam C5 is holding contact 13 closed insures the proper functioning of the signals during the first cycle after they are turned on.

The adaptor can be used with a fixed time control which has only one amber signal circuit. This condition can be simulated by closing switch 16 and opening switches 69 and 73. With this connection the control of relay 7 is transferred from cams C6 and C7 to cam C1 operating in conjunction with relay 6 but relay 7 operates just as it did when controlled by cams C6 and C7. This is accomplished as follows. With relay 6 deenergized as shown in the drawing one side of cam C1 by engaging contact 9 will energize relay 7 through the circuit including switch 16, armature 63, the lower contact associated therewith and wire 20 thus putting positive power on to the right side of the coil of relay 7 which operates it just as if cam C7 had closed contact 15. When the opposite side of cam C1 engages contact 9 relay 6 will have been energized by cam C3 at contact 11 in accordance with the previous explanation and plus power will be sent through armature 63 thereof into its upper contact which leads via wire 71 through resistance 39 to the left side of the coil of relay 7 thereby deenergizing relay 7 just as if cam C6 had closed contact 14. This arrangement makes the adaptor available for use with a fixed time controller incapable of giving two independent amber periods.

A fixed time controller with only one amber

signal circuit is likely to be of the type giving a red signal impulse which does not extend into the amber period on the other street.

Operation of the adaptor by such a controller can be simulated by closing switch 16 and opening switches 69 and 73 (as in the preceding paragraph), opening switches 17 and 18 and moving switches 19 and 32 into their right hand position. With this connection the control of relay 1 is as described in the preceding paragraph and the control of relay 6 is transferred from cam contacts 10 and 11 to cam contacts 12 and 13. The latter two contacts close at the same time as the former two but they open earlier in order to give a signal period not extending into the amber period. However, since relay 6 is operated by the closure of its control contacts, one to energize and the other to deenergize, the fact that cam contacts 12 and 13 do not remain closed for as long a period as contacts 10 and 11, does not alter the cycle of operation of relay 6. Hence, as stated, the adaptor can be operated by a fixed time controller having only an amber signal circuit and in which the red signal impulse does not extend over into the amber period on the other street.

The fact that relays 6 and 7 are so connected that positive power must be connected to their left coil terminals to deenergize them is an important practical feature in that it permits successful operation of the adaptor by a fixed time controller in which the cams are not perfectly adjusted or cam overlaps or gaps occur.

The condenser 33 is used in series with the coil of relay 6 in order to permit connecting positive power to the left side of the coil of relay 6 without incurring a short circuit. Condenser 22 is similarly used in connection with the coil of relay 7. Resistors could be used instead of condensers 33 and 22 but the consequent loss of energy makes the condensers preferable.

The apparatus of the drawing with the signal control switches as shown will, as has been previously stated, give the following signal sequence:

	Period 1	Period 2	Period 3	Period 4	Period 1
Street A.....	Green.....	Amber.....	Red.....	Red.....	Green.....
Street B.....	Red.....	Red.....	Green.....	Amber.....	Red.....

This cycle can be altered by changing the positions of any of the switches 48, 52, 56, 61 or 65. For instance, with switch 56 as shown in the drawing, the B street green signal is deenergized when the B street amber signal is energized. By moving switch 56 to its upper position, the B street green signal will remain energized during the B street amber signal period. This is due to the fact that the control of the B street green signal will now depend solely on armature 40 of relay 6 which engages its upper contact during the B street green and amber periods 3 and 4 as shown in the right hand corner of the drawing.

The B street red signal as shown in the drawing is connected so that it will be energized at the same time as the A street green signal and will remain energized during the A street amber period. However with switch 48 moved to its lower position the B street red signal would not be energized during the A street amber period since its circuit would be interrupted by the separation of armature 45 from its lower contact during the A street amber period. The separation

of armature 45 from its lower contact, however, will not deenergize the phase B red signal so long as there is no call registered by the operation of relay 8 since the bypass circuit through wire 5 41 and armature 42 of relay 8 will be effective to keep the phase B red signal energized.

By moving switch 52 from its shown position to its lower position the A street red signal can be connected so that it will be energized during 10 the B street green signal period but extinguished during the B street amber period. The A street green signal can be caused to remain energized during the A street amber period by moving switch 65 to its lower position. This is evident 15 from the fact that the wire 66 feeding the lower point of switch 65 is connected directly to the bottom contact of armature 40 of relay 6 hence with switch 65 turned down the A street green signal will be energized so long as armature 40 is in its lower position, that is, the A street green and amber periods 1 and 2 shown in the chart 20 in the upper right corner of the drawing.

By closing switch 61 the two amber signals 25 may be connected together so that when either one of them is energized both will be energized thereby giving a common amber period.

By using different combinations of switch positions any one of the standard signal sequences 30 can be obtained. For example, to obtain the following sequence,

	Period 1	Period 2	Period 3	Period 4	Period 1
Street A.....	Green.....	Amber.....	Red.....	Red.....	Green.....
Street B.....	Red.....	Red.....	Green.....	Amber.....	Red.....

the switches would be set as follows. Switch 56 would be left as shown in the drawing thus giving the short green period on B street not running into the amber period. Switch 48 would be changed to the lower position so that the B street red signal would be out during the amber periods. Switch 65 would be left as shown in the drawing inasmuch as this connection gives the green which goes out when the amber comes on. Switch 52 would be moved to its lower position in order to have the A street red signal go out during the amber period. Switch 61 would also be closed.

To obtain the following sequence,

	Period 1	Period 2	Period 3	Period 4	Period 1
Street A.....	Green.....	Green-Am-ber.	Red.....	Red.....	Green.....
Street B.....	Red.....	Red.....	Green.....	Green-Am-ber.	Red.....

the switches would be set as shown in the drawing except that switch 56 would be set in its upper position and switch 65 would be set in its lowered position, which would cause each green signal to remain energized during the amber period in its street. It is obvious that other signal sequences can be obtained by other settings of switches 48, 52, 56, 61 and 65.

The special tap #67 on the transformer T is to provide suitable reduced voltage to operate relays 6 and 7 in series with their condensers 33 and 22 respectively. Resistances could be used in place 70 of condensers 33 and 22 in which case tap #67 could be transferred to the grounded side of the transformer, connected with wire 72. In this case, if the voltage from the source of supply were satisfactory for the detector circuit transformer T could be omitted. Resistances 31 and 39 are

introduced to limit the initial charging current to the condensers 33 and 22 when cam C2 engages with contact 10 and cam C6 engages with contact 14.

The switch 18 is provided to permit the entire apparatus to be disconnected from the power supply.

The switch 18 is provided to permit the signals to be normally extinguished in the absence of traffic when the apparatus is in the rest position if desired. This switch is shown in its normal position for the A green signal and the B red signal to be displayed in the rest position by connection of armature 40 directly to the positive power wire. If it is desired to have the signals normally extinguished switch 18 is moved into contact with wire 79 connected with the motor M circuit so that armature 40 obtains positive power for control of the signals only when the motor has power, that is at all times except when the controller is actually stopped in the rest position of the cycle at the end of the A street green period.

It will be noted from the cam diagram and a comparison of the several signal sequences that the cam contacts of the fixed time controller are closed to provide output power in four periods which may be identified as fixed time signal periods, A green, A amber, B green and B amber in sequence. Some fixed time controllers provide only three cam contacts and output power circuits, one for A green and B red, a second for B green and A red and a third for a common A and B amber energized in both the A and the B amber periods. Others separate the A and B amber circuits and have both green and red periods overlap the amber, and thus add one more cam contact and output power wire making four. Others also have the green signal period end at the beginning of the amber period but have the red on the opposite street overlap the amber period as shown in the case of the six cams C2, C3, C4, C5, C6, C7 in the cam diagram. However in every case it will be observed that there are no output power circuits overlapping three periods in the controller cam contact cycle, whereas to provide for traffic actuated control two such three period power circuits are needed, the first for energizing the motor M, independent of traffic actuation, in the B green, B amber and A green periods, and the second for maintaining the detector relay 8 lock-in circuit (or both the lock-in and operating circuit as illustrated in the present embodiment) throughout the B amber, A green and A amber periods after any momentary operation of this relay by traffic actuation in any of these three periods. Therefore an important feature of the present invention lies in providing relay means which will be operated by the one period and two period power circuits of the controller cams and will combine certain of these periods into certain three period new output power circuits from the relay contacts of such relay means.

Another point to be noted in this connection is that a traffic actuated controller originally designed as such would normally arrange the three period output power circuit for the motor to be interrupted just prior to the end of the A green period so that the controller would be stopped to rest in position with the A green and B red signals energized in the absence of traffic actuation, but that the fixed time controller cam cycle can provide no such arrangement without additional cams for which there is ordinarily

insufficient room. Therefore the present invention in a novel manner makes use of the A amber period of the controller as a rest period to interrupt the motor and places the A green and A amber signals under the control of the output contacts of the relay means of the adaptor so that the A amber signal is kept disconnected and the A green maintained energized in the A amber period of the cam cycle when the controller is at rest and until traffic actuation operates a relay 8 to start the motor and reverse these signal connections so as to restore the usual A amber signal in the A amber period as a cycle of operation is started. The traffic actuated relay 8 controls the motor in the A amber period of the cam cycle, and the relays 6 and 7 control the motor in the other three periods.

It will be appreciated that the detectors 23 are shown in the drawing as simple contact devices for simplicity of illustration and may in practice take any number of other forms.

Although green, amber and red traffic signals are shown and described herein as these are most widely used in street traffic signaling, there are some locations where only green and red signals are employed and a dark period or some form of overlap of the signals provided as a signal change period in place of the amber change period disclosed herein, and it will be appreciated that the invention is not limited to the use of amber signals in the change period.

It will be further understood that the cam-shaft S and cams and cam contacts of the controller comprise a cyclic switching device and that such device may be in the form of a multiple contact drum or other well known forms providing a sequence of output power impulses such as illustrated in the cam diagram.

It will be appreciated by those skilled in the art that various other changes or substitutions may be made in the various parts of the apparatus or an arrangement thereof, without departing from the spirit of the invention as defined in the claims.

I claim:

1. In a traffic control system for intersecting roads having a cyclic switching controller providing a plurality of switches and driving motor means therefor and having a plurality of switch positions through which it is operable by said motor means to provide a time cycle including in sequence a right of way signal period for the main road, a signal change period, a right of way signal period for the cross road, and a second signal change period, means to render said controller operable through said signal cycle in response only to traffic on the cross road, said means comprising means for detecting traffic in the cross road, a relay connected to said traffic detector means to be operated by actuation of the latter by traffic, relay means connected to certain of said switches to be operated thereby in said sequence of periods and having output relay contacts to interrupt said motor in the first said change period and to operate said motor in the other three periods, and contacts operated by the first mentioned relay when actuated to operate said motor, a lock-in circuit for said first relay to maintain this relay operated after detector actuation and including contacts operated by said relay means to interrupt the lock-in circuit in the cross road right of way period and to maintain the lock-in circuit throughout the other three periods after detector actuation.

2. In a traffic control system for intersecting

roads having a cyclic switching controller providing a plurality of switches and driving motor means therefor and having a plurality of switch positions through which it is operable by said motor means to provide a time cycle including in sequence a right of way signal period for the main road, a signal change period, a right of way signal period for the cross road, and a second signal change period, means to render said controller operable through said signal cycle in response only to traffic on the cross road, said means comprising means for detecting traffic in the cross road, a relay connected to said traffic detector means to be operated by actuation of the latter by traffic, relay means connected to certain of said switches to be operated thereby in said sequence of periods and having output relay contacts to interrupt said motor in the first said change period and to operate said motor in the other three periods, said contacts operated by the first mentioned relay when actuated to operate said motor, a lock-in circuit for said first relay to maintain this relay operated after detector actuation and including contacts operated by said relay means to interrupt the lock-in circuit in the cross road right of way period and to maintain the lock-in circuit throughout the other three periods after detector actuation, additional contacts operated by said first relay in absence of actuation to energize the main road right of way signal and interrupt the first change signal in said first change period and upon actuation to interrupt said main right of way signal and to energize said first change signal in said first change period.

3. In a traffic control system for intersecting roads having a cyclic switching controller providing a plurality of switches and driving motor means therefor and having a plurality of switch positions through which it is operable by said motor means to provide a time cycle including in sequence a right of way signal period for the main road, a signal change period, a right of way signal period for the cross road, and a second signal change period, means to render said controller operable through said signal cycle in response only to traffic on the cross road, said means comprising means for detecting traffic in the cross road, a relay connected to said traffic detector means to be operated by actuation of the latter by traffic, relay means connected to certain of said switches to be operated thereby in said sequence of periods and having output relay contacts to interrupt said motor in the first said change period and to operate said motor in the other three periods, said contacts operated by the first mentioned relay when actuated to operate said motor, a holding device for said first relay to maintain this relay operated after detector actuation and including contacts operated by said relay means to interrupt the holding device in the cross road right of way period and to maintain the holding device operative throughout the other three periods after detector actuation, additional contacts operated by said first relay in absence of actuation to energize the main road right of way signal and interrupt the first change signal in said first change period and upon actuation to interrupt said main right of way signal and to energize said first change signal in said first change period.

4. In a traffic control system for intersecting roads having a cyclic switching controller providing a plurality of switches and driving motor

means therefor and having a plurality of switch positions through which it is operable by said motor means to provide a time cycle including in sequence a right of way signal period for the main road, a signal change period, a right of way signal period for the cross road, and a second signal change period, means to render said controller operable through said signal cycle in response only to traffic on the cross road, said means comprising relay means for actuation by traffic in the cross road to operate said motor and further relay means operated by said switches to combine the second change period and main right of way period and first change period into one output period for operation of the traffic actuated relay means in said three periods after initial actuation by traffic, and to combine the cross right of way period and second change period and main right of way period into another output period for operation of said motor through the remainder of one complete cycle after initial operation by said traffic actuated relay means.

5. In a traffic control system for intersecting roads having a cyclic switching controller providing a plurality of switches and driving motor means therefor and having a plurality of switch positions through which it is operable by said motor means to provide a time cycle including in sequence a right of way signal period for the main road, a signal change period, a right of way signal period for the cross road, and a second signal change period, means to render said controller operable through said signal cycle in response only to traffic on the cross road, said means comprising relay means for actuation by traffic in the cross road to operate said motor and further relay means operated by said switches to combine the second change period and main right of way period and first change period into one output period for operation of the traffic actuated relay means in said three periods after initial actuation by traffic, and to combine the cross right of way period and second change period and main right of way period into another output period for operation of said motor through the remainder of one complete cycle after initial operation by said traffic actuated relay means and contact means operated by said traffic actuated relay means in absence of actuation to energize the main road right of way signal and interrupt the first change signal in said first change period and upon actuation to interrupt said main right of way signal and to energize said first change signal in said first change period.

6. Traffic control apparatus for converting a fixed time cyclic right of way signal control system having a time cycle including four periods into a traffic actuated right of way signal control system, comprising a traffic detector device, a relay having an operating circuit connected with said device to be operated by traffic actuation of the latter and having a lock-in circuit to maintain the relay operated after such actuation, relay means having input operating circuits for individual operation in certain of the four periods of the time cycle and having an output circuit providing output power overlapping three of said four periods, and a connection between said output circuit and the lock-in circuit of the traffic actuated relay to maintain the lock-in circuit effective throughout said three periods and interrupt the same in the fourth period.

7. Traffic control apparatus for converting a fixed time cyclic motor operated right of way signal control system having a time cycle including four periods into a traffic actuated right of way signal control system, comprising a traffic detector device, a relay having an operating circuit connected with said device to be operated by traffic actuation of the latter and having a lock-in circuit to maintain the relay operated after such actuation, relay means having input operating circuits for individual operation in certain of the four periods of the time cycle and having an output circuit providing output power overlapping three of said four periods, and a connection between said output circuit and the lock-in circuit of the traffic actuated relay to maintain the lock-in circuit effective throughout said three periods and interrupt the same in the fourth period, another three period output circuit from said relay means to operate said motor in the latter three periods and interrupt the motor to stop cyclic operation in a different fourth period of the cycle, and an output circuit from said traffic actuated relay to operate said motor when said traffic actuated relay is operated.

8. Traffic control apparatus for converting a fixed time cyclic motor operated right of way signal control system having a time cycle including four periods into a traffic actuated right of way signal control system, comprising a traffic detector device, a relay having an operating circuit connected with said device to be operated by traffic actuation of the latter and having a lock-in circuit to maintain the relay operated after such actuation, a second relay having an operating input circuit for energization in the second of the four periods of the time cycle and a lock-in circuit to maintain it operated in the second and third periods and having another input circuit to short circuit said second relay in the fourth period to deenergize said second relay in the fourth and first periods, a third relay having an operating input circuit for energization in the third period of the cycle and a lock-in circuit to maintain it operated in the third and fourth periods and having another input circuit to short circuit said third relay to deenergize the same in the first and second periods, contacts operated by the respective relays, an output circuit including contacts closed by said second and third relays when either one is deenergized and connected to the lock-in circuit of said first relay to render the latter effective in said second, fourth and first periods and interrupt the latter in said third period, a second output circuit including contacts operated by said second and third relays when the second relay is deenergized and also when the third relay is energized to provide output power overlapping said third, fourth and first periods for operation of said motor in these periods and interruption of the motor in said second period, and an output circuit including contacts closed by operation of said first relay to operate said motor when said first relay is operated.

9. Traffic control apparatus for converting a fixed time cyclic motor operated right of way signal control system, having a power output cycle including a main right of way period, a main change period, a cross right of way, and a cross change period in the sequence stated, into a traffic actuated right of way signal control system, comprising means to detect the presence of cross traffic, a relay having an operating circuit

connected with said device to be operated by traffic actuation of the latter and having a lock-in circuit to maintain the relay operated after such actuation, a second relay having an operating input circuit for energization in the main change period and a lock-in circuit to maintain it operated in said main change period and the following cross right of way period and having another input circuit to short circuit said second relay in said cross change period to deenergize said second relay in said cross change period and the following main right of way period, a third relay having an operating input circuit for energization in the cross right of way period and having another input circuit to short circuit said third relay in said main right of way period to deenergize the same in said main right of way period and the following main change period, contacts operated by the respective relays, an output circuit including contacts closed by said second and third relays when either one is deenergized and connected to the lock-in circuit of said first relay to render the latter effective in said cross change, said main right of way, and said main change periods and to interrupt the latter in said cross right of way period, a second output circuit including contacts operated by said second and third relays when the second relay is deenergized and also when the third relay is energized to provide output power overlapping said cross right of way, said cross change and said main right of way periods for energization of the motor in the last mentioned three periods and interruption of the motor in said main change period, and an output circuit including contacts closed by operation of said first relay to operate said motor when said first relay is operated.

10. Traffic control apparatus as in claim 9 in which a signal power output circuit for the main right of way signal is provided through contacts on said relays from a connection with the operating circuit of said motor whereby the signals will be deenergized normally in the main change period when the motor is interrupted by absence of traffic actuation.

11. Traffic control apparatus for converting a fixed time cyclic motor operated right of way signal control system, having a power output cycle including a main right of way period, a main change period, a cross right of way, and a cross change period in the sequence stated, into a traffic actuated right of way signal control system, comprising means to detect the presence of cross traffic, a relay having an operating circuit connected with said means to be operated by traffic actuation of the latter and having a lock-in circuit to maintain the relay operated after such actuation, a second relay having an operating input circuit for energization in the main change period and a lock-in circuit to maintain it operated in said main change period and the following cross right of way period and having another input circuit to short circuit said second relay in said cross change period to deenergize said second relay in said cross change period and the following main right of way period, a third relay having an operating input circuit for energization in the cross right of way period and having another input circuit to short circuit said third relay in said main right of way period to deenergize the same in said main right of way period and the following main change period, contacts operated by the respective relays, an output circuit including contacts closed by said second and third relays when either one is deen-

ergized and connected to the lock-in circuit of said first relay to render the latter effective in said cross change, said main right of way, and said main change periods and to interrupt the latter in said cross right of way period, a second output circuit including contacts operated by said second and third relays when the second relay is deenergized and also when the third relay is energized to provide output power overlapping said cross right of way, said cross change and said main right of way periods for energization of the motor in the last mentioned three periods and interruption of the motor in said main change period, and an output circuit including contacts closed by operation of said first relay to operate said motor when said first relay is operated, a third output circuit including contacts closed by said third and first relays when both are deenergized to supply power for energization of the main right of way signal in the main change period in absence of traffic actuation, a fourth output circuit including contacts closed by all three said relays when said first and second relays are energized and said third relay is deenergized to supply power for energization of the main change signal in the main change period upon traffic actuation, and additional output circuits including contacts operated by said second and third relays to provide output power for energization of the main right of way, cross right of way and cross change signals in their respective periods whereby said signals will be energized continuously throughout their respective periods despite any momentary interruptions of the power output from the switches of said cyclic controller during such respective periods.

12. Traffic control apparatus for converting a fixed time cyclic motor operated right of way signal control system, having a power output cycle including a main right of way period, a main change period, a cross right of way, and a cross change period in the sequence stated, into a traffic actuated right of way signal control system, comprising means to detect the presence of cross traffic, a relay having an operating circuit connected with said means to be operated by traffic actuation of the latter and having a lock-in circuit to maintain the relay operated after such actuation, a second relay having an operating input circuit for energization in the main change period and a lock-in circuit to maintain it operated in said main change period and the following cross right of way period and having another input circuit to short circuit said second relay in said cross change period to deenergize said second relay in said cross change period and the following main right of way period, a third relay having an operating input circuit for energization in the cross right of way period and having another input circuit to short circuit said third relay in said main right of way period to deenergize the same in said main right of way period and the following main change period, contacts operated by the respective relays, an output circuit including contacts closed by said second and third relays when either one is deenergized and connected to the lock-in circuit of said first relay to render the latter effective in said cross change, said main right of way, and said main change periods and to interrupt the latter in said cross right of way period, a second output circuit including contacts operated by said second and third relays when the second relay is deenergized and also when the third relay is energized to provide output power over-

lapping said cross right of way, said cross change and said main right of way periods for energization of the motor in the last mentioned three periods and interruption of the motor in said main change period, and an output circuit including contacts closed by operation of said first relay to operate said motor when said first relay is operated, a third output circuit including contacts closed by said third and first relays when both are deenergized to supply power for energization of the main right of way signal in the main change period in absence of traffic actuation, a fourth output circuit including contacts closed by all three said relays when said first and second relays are energized and said third relay is deenergized to supply power for energization of the main change signal in the main change period upon traffic actuation.

13. Traffic control apparatus as in claim 12 in which the output power circuit for energization of the main right of way signal through the relay contacts as aforesaid is connected for power source only to the operating circuit of said motor whereby the signals will be deenergized normally in the main change period when the motor is interrupted by absence of traffic actuation.

14. Traffic control apparatus for converting a fixed time cyclic signal controller having a four period cycle with power output individual to one period and two periods only of said four periods into a controller adapted to have its signal cycle initiated by traffic actuation, said apparatus comprising relay means having power input operating circuits for energization of the relay means in one period and for short circuit of the relay means for deenergization in a subsequent period, and power output circuits including contacts operated by said relay means to energize said output circuits during three of said four periods.

15. Traffic control apparatus for connection to a cyclic signal controller having a four period time cycle and power output circuits energized individually in single periods of said cycle, said apparatus comprising relay means having input operating circuits for connection to certain of said power output circuits for operation of said relay means individually in said periods and having other output circuits including contacts operated by said relay means and combined to provide output power overlapping three of said four periods.

16. Traffic control apparatus for connection to a cyclic signal controller having a four period time cycle and one power output circuit energized in the first of said four periods, a second output circuit energized in the third of said periods, and a third output circuit energized in the second and fourth of said periods, said apparatus comprising relay means having input operating circuits for connection to certain of said output circuits and having other output circuits including contacts operated by said relay means and combined to provide output power overlapping the third and fourth and first periods on one of the last named circuits and overlapping the fourth, first and second periods on another of said last named circuits.

17. Traffic control apparatus for connection to a cyclic signal controller having a four period time cycle and power output circuits energized individually in single periods of said cycle, said apparatus comprising relay means having coils and contacts operated thereby, input operating circuits for said coils for connection to certain of said power output circuits for operation of said

coils individually in certain of said periods, and further output circuits including said contacts and connected together to provide output power overlapping three of said four periods.

18. Traffic control apparatus for converting a fixed time cyclic signal controller having a four period cycle with power output individual to one period and two periods only of said four periods into a controller adapted to have its signal cycle initiated by traffic actuation, said apparatus comprising relay means having power input operating circuits for energization of the relay means in one period and for short circuit of the relay means for deenergization in a subsequent period, and power output circuits including contacts operated by said relay means to energize said output circuits during three of said four periods, traffic actuated relay means having a stick circuit connected to one of said three period power output circuits for maintaining said traffic actuated relay means in actuated condition throughout said three periods after momentary traffic actuation therein and for releasing said traffic actuated relay means from actuated condition in said fourth period.

19. Traffic control apparatus for converting a fixed time cyclic signal controller having a four period cycle with power output individual to one

period and two periods only of said four periods into a controller adapted to have its signal cycle initiated by traffic actuation, said apparatus comprising relay means having power input operating circuits for energization of the relay means in one period and for short circuit of the relay means for deenergization in a subsequent period, and power output circuits including contacts operated by said relay means to energize said output circuits during three of said four periods, traffic actuated relay means having a stick circuit connected to one of said three period power output circuits for maintaining said traffic actuated relay means in actuated condition throughout said three periods after momentary traffic actuation therein and for releasing said traffic actuated relay means from actuated condition in said fourth period, said controller having a motor for driving the controller through its cycle, and said apparatus including an operating connection for said motor to another of the said three period output circuits for operation of said motor during only the latter three periods, and another operating connection for said motor from said traffic actuated relay means for operation of said motor when the latter relay means is in actuated condition.

JOHN L. BARKER.
